UNITED STATES PATENT OFFICE

148,460

DESIGN FOR A HYDRAULIC BUMPER JACK

Harold W. Darr, Minneapolis, Minn., assignor to
 Midwestern Metal Products Co., Minneapolis,
 Minn., a corporation of Minnesota

Application March 11, 1946, Serial No. 127,357

Term of patent 14 years

(Cl. D41—1)

To all whom it may concern:

Be it known that I, Harold W. Darr, a citizen of the United States, residing at Minneapolis, in the county of Hennepin and State of Minnesota, have invented a new, original, and ornamental Design for a Hydraulic Bumper Jack, of which the following is a specification, reference being had to the accompanying drawing, forming part thereof.

Referring to the drawing:

The single figure is a perspective side view of a hydraulic bumper jack showing my new design, the side not shown being identical to the side shown.

I claim:

The ornamental design for a hydraulic bumper jack, as shown and described.

HAROLD W. DARR.
